UNITED STATES PATENT OFFICE.

JAMES A. MCGEE, OF NEW YORK, N. Y., ASSIGNOR TO EMILY CECELIA
McGEE, OF SAME PLACE.

SOFA-BEDSTEAD.

SPECIFICATION forming part of Letters Patent No. 246,175, dated August 23, 1881.

Application filed July 5, 1881, (No model.)

To all whom it may concern:

Be it known that I, JAMES ALEXANDER MCGEE, a citizen of the United States, residing at New York, in the county of New York and State of New York, have invented certain new and useful Improvements in Sofa-Bedsteads; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 This invention relates to sofa-bedsteads; and the object of the invention is to economize space, cheapen the construction, and afford a convenient and compact receptacle for the bedding used to cover the extensible part of the sofa.

20 Heretofore this class of furniture has been constructed with an extension which could be turned outwardly in a horizontal plane with the sofa proper by means of hinges attaching 25 it thereto, and the mattress was either made integral therewith or else was separate, and when not used on the sofa had to be stowed away in a place other than the sofa. Receptacles for portions of the bedding have been 30 made in the sofa proper. Further, drawers have been made in the sofa, beneath its upholstered seat, adapted to receive various articles; but so far as I am aware such drawers have not been constructed to contain the mattress and the other bedding wholly within 35 them, so that when not in use such mattress and bedding could be completely inclosed within such drawers, pushed under the sofa, and thus hid from sight.

40 My invention consists in applying to a sofa-bedstead a drawer of considerable depth and sufficient to contain within it the mattress and other bedding necessary to complete the bed when such drawer shall have been extended to 45 make out the bed. This drawer is provided with a close cover, which fits down over its top so as to wholly inclose the bedding and protect it from dust, the said cover serving as

a support for the mattress and bedding when the sofa is used as a bed.

50 The invention further consists in details of construction hereinafter specified and claimed.

In the accompanying drawings, in the several figures of which like parts are similarly designated, Figure 1 is a perspective view of 55 one of my improved sofa-bedsteads extended for use. Fig. 2 is a longitudinal vertical section thereof. Fig. 3 is a perspective view of a modification with the drawer extended for use. Fig. 4 is a vertical cross-section with the 60 drawer shoved under the sofa-seat to adapt the sofa for use as such.

A designates the sofa proper, which may be of any ordinary construction. In the prevailing Queen Anne style of furniture the base B 65 of the sofa is quite deep and extends close to the floor, the sofa being usually supported solely by casters. This base B is utilized, on account of its depth, to receive a drawer, C, which is adapted to slide in and out of said 70 base in the usual manner of operating drawers; and I provide this drawer with a close or tight cover, D, fitting down over the top of the drawer and preferably hinged to the rear or inner edge thereof, so as to be capable of being lifted up to obtain access to the interior of the drawer. This drawer is of sufficient length and depth to receive within it all of the bedding, including the mattress, and by means of its cover D such bedding is preserved from 75 dust. The provision of this bedding-receiving drawer obviates the necessity of finding a place for the bedding, and in apartment-houses, where sofa-bedsteads are most in demand, this economy of space will be appreciated as a great 80 desideratum.

85 As seen in Fig. 1, the mattress E covers the top of the drawer only, the upholstering on the sofa proper forming a mattress for that portion of the bed. This division of the mattress will be found convenient in that the mattress, which is to be handled, is correspondingly smaller and lighter.

90 The drawer C will be provided with casters F, and suitable handles may be attached for 95 ease in working it. I provide for this drawer

a removable head-rest, G, which may or may not be upholstered. This head-rest is provided with legs H, which extend down through slots I in the cover D to the bottom of the drawer, 5 where they abut against a cross-piece or stop, J, whereby the head-rest is retained at the desired inclination. When not in use this head-rest may be easily taken out of the slotted cover and placed within the drawer.

10 A longitudinal guard, K, may be permanently affixed to the drawer C, to keep the bed-clothing on the drawer, as shown in Fig. 1; but this guard may be hinged or otherwise movably attached to the drawer, as indicated 15 in Fig. 4, this last being the preferred construction. If hinged or removable, the guard-piece, when not in use, will be placed within the drawer. If such guard-piece is fixed it may be in the nature of a molding at the top 20 of the drawer, forming, when the sofa is used as a sofa, a beading about the lower edge of the upholstered seat of the sofa.

25 In Fig. 3 the head-piece L is hinged to the hinged cover D, and is supported at the desired inclination by a brace or standard, M. When not in use this hinged head-rest may be folded down over the cover D, and a space, N, being left between the cover and the bottom of the sofa-seat sufficiently large to receive 30 this folded-down head-rest, the drawer may be pushed underneath the sofa-seat, as before. The use of the head-rest, while desirable, is not necessary.

What I claim is—

1. In a sofa-bedstead, the drawer C, continuous 35 of its length, and adapted to be slid in and out beneath the sofa-seat, and provided with a close cover, D, fitting down tight over the drawer, whereby a closed receptacle is provided for all of the bedding employed, substantially as described.

2. The combination of the sofa proper, A, and its base B, with the drawer C, forming an extension thereof, and adapted to receive and inclose all the bedding when not in use, and a 45 close cover, D, arranged above said drawer to make a tight drawer thereof, and also to serve as a support for the bedding when in use, substantially as shown and described.

3. In a sofa-bedstead, the drawer C, arranged 50 to slide in and out beneath a sofa-seat, as shown, combined with a hinged cover, D, and an attachable head-rest, substantially as specified.

4. In a sofa-bedstead, the drawer C, provided with the longitudinal guard hinged thereto and adapted to be folded within the drawer when not in use, substantially as and for the purpose described.

In testimony whereof I affix my signature in presence of two witnesses.

JAMES ALEXANDER McGEE.
